TELEPHONE TRANSMITTER

Ernest S. McLarn, Manhasset, N. Y., assignor to
International Standard Electric Corporation,
New York, N. Y., a corporation of Delaware

Application March 31, 1937, Serial No. 134,044

9 Claims. (CL 179—122)

This invention relates to telephone apparatus and pertains more particularly to telephone transmitters.

It is an object of my invention to provide an improved form of variable resistance element, which is moisture proof and resistant to atmospheric changes.

More specifically, it is an object of my invention to provide an improved form of telephone transmitter wherein the carbon granules or other resistance elements are enclosed in a moisture proof housing.

A still further object of my invention is to provide a variable resistance element which is especially adapted for use in a telephone transmitter, which element is compact, simple in construction and low in cost.

Another object of my invention is to provide a telephone transmitter variable resistance element which has a relatively high heat dissipating capacity and therefore a high current carrying ability.

Telephone transmitters constructed in accordance with the teachings of the prior art, for example, those utilizing a silk bag for holding the carbon granules, have at times given a considerable amount of trouble due to moisture precipitated on the active parts thereof during particularly humid weather. This effect has been encountered to a certain extent in the tropics, for example. A further disadvantage has been that certain of the metal parts of the transmitter have been subject to atmospheric corrosion and electrolytic action, which has interfered with the effective operation thereof and limited the life of the instrument.

In accordance with my invention the carbon granules are enclosed in a flexible metallic bellows which serves as a carbon chamber, this chamber being made air and water tight by suitable closures, the entire carbon chamber or bellows being compressed by the voice waves impinging on the transmitter diaphragm whereby the resistance of the carbon granules is varied and the output current of the device accordingly controlled. Insulation for the inside of the metal bellows may be provided by any suitable means such as a coating of insulating varnish, this being applied, for example, by dipping the entire bellows in liquid varnish and subsequently subjecting it to a drying operation before the carbon granules are inserted. Other insulating material might be provided inside the bellows since moisture and air are excluded therefrom. The silk material formerly used for making the carbon bag or chamber might be used for this insulation, either by itself or in cooperation with a layer of insulating varnish such as already described.

The metal bellows is preferably of brass or

aluminum having a thickness of only a few thousandths of an inch; although the thickness may be varied. It will usually be found that with spring brass of ordinary quality a thickness of the order of a few thousandths of an inch, that is, about the thickness of paper, may be used successfully. The metal bellows being almost wholly elastic results in a more perfect reproduction of the human voice than other material which is less elastic, for example, silk. The metal bellows being substantially in contact with the carbon granules serves readily to conduct the heat therefrom, whereby a greater amount of current can be passed through the transmitter button or variable resistance than would be the case if the carbon material were enclosed in an insulating chamber which would have a poorer heat conductivity than the metal of which the bellows is formed.

The above mentioned and further objects and advantages of my invention and the manner of attaining them will be more fully explained in the following description taken in conjunction with the accompanying drawings.

In the drawings, Fig. 1 shows in side elevation and partly in section a telephone transmitter assembly constructed in accordance with my invention; Fig. 2 shows a modified form of construction using a slightly different shape of metal bellows; Fig. 3 illustrates another modification wherein a different type of seal is utilized; Figs. 4, 5, 6 illustrate still further embodiments of my invention; Figs. 7 and 8 illustrate in side elevation a closure for the transmitter unit; and Fig. 9 illustrates in side elevation and partly in section yet another embodiment of my invention.

Referring more particularly to the drawings, reference numeral 1 indicates a telephone transmitter housing of any suitable insulating material having fixed thereto, for example by a molding in process, metal rings 2 and 3, which are held in spaced relation by spacing posts 4 which interconnect the rings electrically. Centrally disposed with respect to the rings 2 and 3 and insulated therefrom, is a metal nut insert 5, which serves to hold the transmitter button assembly or variable element 6 in position. The transmitter button comprises a metal bellows 7, which may be of brass, aluminum or the like, of a springy nature and a thickness of a few thousandths of an inch, e. g. approximating that of writing paper, this bellows being coated on the inside with insulating varnish enamel or similar insulating material as indicated by reference numeral 8. The side walls of the bellows are made reentrant at the lower end thereof, thereby providing an end closure, this end closure being apertured at the center thereof. A back electrode or pressure element 9 is positioned inside of the bellows 7, this element having a threaded shank 60

10 which passes loosely through the aperture 11 of the chamber, not touching the edges thereof, this pressure element being insulated from the bellows by means of washers 12 of mica or other insulating material. The entire pressure element 5 is held against movement by means of nut 13 threaded on the shank 10, the latter being in turn screw threaded into the nut 5, which is molded into the housing 1, thereby bringing the bellows 10 into direct contact and electrical connection with the metal rings 2 and 3. The ring 2 with the nut 5 serve as terminals whereby electrical connection can be made with the transmitter unit.

The interior of the metal bellows or carbon chamber 7 is filled with a mass of granulated carbon 14 and the upper end of the bellows is closed by means of a cap 15 which is crimped and/or soldered to the upper edge of the bellows 7. This cap has an indented center portion 16 which acts as a front electrode or second pressure element thereby serving, upon the application of pressure to the end plate, to compress the carbon granules between the end plate and the back electrode 9, this compression causing a variation in resistance and a desired control of the current passing through the device. Reference numeral 16 indicates a corrugated diaphragm of anodic aluminum, duralumin or other light, springy material such as Bakelized silk which is supported at its periphery between two washers of phenol fibre or other similar material indicated by 17. These washers are compressed so as to hold the diaphragm in position, by means of a perforated closure or cap 18 which is crimped or otherwise fastened to the housing 1 at 19. The arrangement of parts is such that the diaphragm normally presses lightly against the cover 15 of the bellows, preferably being electrically insulated therefrom by means of a washer 20 of mica, phenol fibre or other suitable insulating material. Reference numeral 42 indicates a seal of high melting point wax or other suitable material which serves further to prevent access of air and moisture to the inside of the bellows.

From the foregoing description it will be seen that the carbon granules inside of the element 6 are prevented from contact with the air and from the deleterious effects of moisture by the 50 screw connection and washer 12, and the wax seal 42 at the base thereof and by means of the soldered cover 15 at the top thereof. At the same time electrolysis and resulting corrosion of the transmitter diaphragm 16 is eliminated 55 by insulating this element from the top of the bellows 7 through use of the insulating washer 20, the outer edge of the diaphragm being, at the same time, free from connection with metal parts.

60 Fig. 2 illustrates a somewhat similar construction with the exception that the metal bellows has the upper portion 21 formed integrally with the side 22 thereof, the final closure or cover 23 being at the bottom thereof, the connection between the two parts being by means of soldering or welding. In this modification the bellows has been shown as barrel shaped instead of corrugated as in Fig. 1, but the method of forming the top and bottom closures may be the same 65 as that used with other shapes of bellows.

Fig. 3 illustrates a still further embodiment of my invention wherein the carbon chamber comprises a side wall 24 of cylindrical shape closed at the top by means of a flap 25 and having integrally formed with the lower end thereof a flex-

ible corrugated diaphragm portion 26 having a central aperture 27 therein. Positioned in the aperture just mentioned and surrounding post 28 of back electrode 29 is a bead of glass or other insulating material 30, which serves hermetically 5 to seal the carbon container. In case that a glass bead is used at this point a satisfactory seal may be formed by welding or fusing the glass to the diaphragm and to the post 28 in air tight fashion in accordance with the teachings of the vacuum tube and electric light art. Under the back electrode 29 is a mica washer 31 which supports the carbon granules. Suitable means such as a second washer of phenol fiber or other suitable material 32 is provided to hold the mica washer 15 in position, the second mentioned washer 32 being held in position by a friction grip with the post 28, preferably being a drive fit therefor. The post 28 is soldered or riveted into a bushing 33 molded in the housing 1 thereby making a first 20 connection, while the second connection, that is, the connection to the diaphragm 26, is made by means of a wire 34 electrically connected to a second bushing 36 molded in the housing 1. While this welded glass seal is shown in connection with a straight side bellows having a flexible diaphragm at the bottom thereof, the seal may also be used with other types of bellows, such for example as shown in the other figures of the drawings.

The structure of Fig. 4 is somewhat similar to that of Fig. 3, except that the center post 28 is screw threaded to a nut 37 imbedded in the housing 1 and that the carbon chamber 24 is contacted at its lower end directly with two rings 38 and 39 molded in the housing 1, these rings being spaced by members 40 which connect the rings electrically, and being insulated from the nut 37 in substantially the same way as described in connection with Fig. 1. In this device the 40 flexibility of the unit is secured by means of a corrugation 41 placed in the side walls of the container 24. Seals of high melting point wax or the like are provided at points 42 and 43.

In Fig. 5 the construction of the housing and 45 metallic insert is the same as in Fig. 1, the difference in the structure residing principally in the manner of securing the metal bellows to the housing. In this case the metal bellows has at its lower end an inwardly turned flange 44 resting on the conducting ring 3. A washer of phenol fiber or other insulating material 45 is positioned between the pressure element 9 and the inwardly turned flange, the screw threaded connection between post 10 and nut 5 serving to hold 50 the entire assembly in rigid position. Reference numeral 42 indicates a wax seal similar to that shown in Fig. 1, for the purpose of preventing the entrance of moisture. In this figure an alternative form of arrangement with respect to the transmitter diaphragm is shown. The diaphragm has a central aperture at 45', through which a screw threaded projection 46 of the cap 15 projects, the diaphragm being firmly fixed to the element 15 by means of a nut of phenol fiber 65 or other insulating material 47. A washer 48 is furnished to insulate the diaphragm 16 from the element 15.

In Fig. 6 the construction of the housing 50 is somewhat different from that of the other 70 figures, being of metal. This housing has an aperture at the lower side thereof through which passes a post or shank 51, the upper end of which forms a back electrode 52. Between the back electrode portion and the shank is a shoulder 53 75

which is sealed by a glass bead 54 directly to an offset washer 55. This offset washer is soldered to the lower end of bellows 56 and rests against a thin corrugated spring washer 57 of brass or other suitable conductor. Washers 58 of phenol fibre or other suitable material serve to insulate the post and back electrode from the case or housing 59, the entire assembly being drawn together by a nut 59 which presses against a brass washer 60.

At the upper end of the bellows 56 is located a front electrode 61, this electrode being soldered to the upper end of the bellows, although the electrode may alternatively be made integral with the bellows. The front electrode is shown as hemispherical in shape but it need not be so formed, a flat electrode likewise being suitable. This upper electrode is formed of thin metal pressed to the desired shape and has in it a plurality of small holes 63 having a diameter of about .01 inch or less. Soldered to the upper side of the front electrode is a second bellows 64 which is very much weaker than the bellows 56 so that when any expansion of air or other gas 55 inside of the space enclosed by the bellows takes place, the upper small bellows 64 instead of the main bellows 56, will expand to take care of the increased pressure whereby any appreciable displacement between the front and back electrodes 61 and 52, respectively, is prevented from occurring. In place of the upper small bellows 64 an expansion chamber of vulcanized neoprene, natural rubber or the like, may be provided. For example, a disc of this material may 35 be cemented or clamped to the upper side of the front electrode 61 thereby forming a closure which will bulge outwardly as the pressure within the main bellows increases with a rise in temperature. Such a rise in temperature might result from prolonged operation of the transmitter or from its use in an atmosphere subject to wide temperature changes.

In place of a solid front electrode 61 pierced by a plurality of small holes, a wire mesh electrode 45 might be used, the mesh being one hundred or finer, for example, such a mesh screen might be of brass, gold plated. The other electrodes described in the present application might also be gold plated although it may be found possible 50 in certain cases to omit this gold plated joint formed by the construction described. Alternatively the surfaces of the electrodes may be of polished carbon. This will be particularly true in case a relatively inert gas, such as nitrogen 55 or the like is used inside of the bellows. Obviously in Fig. 6, as in the other figures, the space inside of the bellows is filled with granular carbon.

In Fig. 6 the closure or cap 18 is of a collapsible type adapted for easy removal and replacement, as will be explained more fully in connection with Figs. 7 and 8. This cap has near its outer edge an indented ring 65 which is adapted to engage the outer edge of the diaphragm 66, no gaskets being provided. The diaphragm is apertured at the center portion to engage the bellows 56 and at the same time provide an opening for the auxiliary bellows or expansion chamber 64. The cap when placed in position 70 engages the outer edge of the diaphragm and places it under a slight bending force which causes the diaphragm firmly to engage the top of the bellows 56. This type of construction has been found to lessen distortion of the diaphragm 75 and as a result improve the quality of transmis-

sion of sound. This method of holding the diaphragm is not limited to the structure shown in Fig. 6 but may be used with other structures, for example, such as shown in the preceding figures.

In Figs. 7 and 8 the closure or cap 18 is of the collapsible type having a flange 66 which is divided into a plurality of sections or fingers 67, which serve normally to grip the sides of the housing 1, as shown in Fig. 6, for example. By 10 pressing on the end of the cap the fingers are spread apart as shown in Fig. 7, in which condition the cap can be placed on or removed from the housing. The resilient squeezing action of the fingers when in gripping position causes the 15 diaphragm 16 to be held firmly and resiliently against the bellows as shown in Fig. 6 or between the cork washers 17 as illustrated in Fig. 1, and thereby prevents the diaphragm from becoming loose. Furthermore, the cap can be 20 quickly and easily removed without tools for inspection and repairs.

Fig. 9 illustrates a transmitter somewhat similar to that of Fig. 6. The variable resistance unit has a slightly different construction 25 in that the upper portion 10 is dome shaped, forming the front electrode. The back electrode 71 is of a roughly similar shape and has a shank 72, either screw threaded thereto as shown, or integral therewith, and the shank is sealed by 30 glass bead 73 to a disc 74 of copper or other suitable material, in the same manner as in the structure of Fig. 6. The metal bellows 75 is crimped or soldered, or both, to the edge of the disc 74, preferably so as to form an air tight seal. 35

The self-contained resistance unit above described is centered with respect to the housing 50 by means of a ring 75 embossed in the housing, this ring just fitting within the end 76 of the metal bellows, the whole resistance unit being 40 held in position by nut 77 on the screw threaded portion of the shank 72. This nut presses against a metal washer 78 and insulating washer 79 thereby drawing the copper disc 74 and attached metal bellows down against the embossed 45 ring 75. A shoulder 80 on the shank 72 prevents too great strain being placed on the copper disc and glass seal, this shoulder being located so as to seat against the washer 78 when the nut 77 has been screwed on far enough to draw the 50 copper disc firmly against the embossed ring 75, a slight deflection of the copper disc after the pressing thereof firmly against the embossed ring serving to permit the shoulder 80 to engage insulating washer 79. 55

The interior of the metal bellows is preferably gold plated and the back electrode may be of brass, gold plated, or may be of carbon. The inside of the metal bellows is filled full of granular carbon constantly shaken during the filling process so that no void spaces will be left when the unit is completely assembled. The entire inner surface of the bellows acts as an electrode and therefore need not be provided with an insulating coating although, if desired, insulation in 60 the form of varnish enamel or the like may be provided for the inside of the convolutions of the bellows leaving only the dome shaped top portion to act as a front electrode. The seal disc 74 is 65 preferably insulated on the upper surface thereof by means of a coat of varnish enamel or by use of a very thin mica washer as indicated by reference numeral 81. Because of the fact that the use of insulation is largely avoided and substantially the entire bellows is used as an elec- 70 75

trode surface, the current carrying capacity of the device constructed as shown in Fig. 9 is high.

While in many instances it may be desirable to have the housing 50 solid so as completely to enclose the resistance unit, additional cooling effect can be obtained by having openings in the housing 50 or by making this housing in the form of a spider having a plurality of radiating arms which extend to the rim which holds the cap 18. In Fig. 9, as in Fig. 6, the diaphragm, which may be of anodic aluminum, bakelized silk or other resilient material of small inertia, is pressed against the end of the metal bellows by action of the cap 18, but is otherwise unsupported. However, any conventional method of holding the diaphragm in position might be used. With the device of Fig. 9, an expansion chamber such as disclosed in connection with Fig. 6, might also be used if desired.

The invention has been particularly described as applied to a telephone transmitter but it will be obvious that the general features of construction are useful in other fields and that a variable resistance element of the general type described may be used in many different ways. This moisture proof variable resistance element is, for example, adapted for use in electro-mechanical repeaters, and likewise in hearing aids such as audiophones. It is also well adapted for incorporation in various kinds of recording instruments wherein a change of condition is indicated by a change of pressure, such for example, as depth gauges, altimeters and barometers, for sound detection under water or in the air and for temperature recording. In the latter instance the pressure may be supplied by means of an external force, e. g. a bimetallic spring or the metal bellows itself may be made bimetallic so that it will distort under variation in temperature, or the air within the metallic chamber may be relied upon to vary the pressure to which the carbon granules are subjected, an increase in temperature resulting in an expansion of the air and a reduction of the pressure on the carbon granules, which follows from an increase in the spacing between the pressure element of the device. Alternatively, in place of air the bellows may be filled with some other form of expandible gas which is responsive to temperature changes.

While I have described particular embodiments of my invention for purposes of illustration, it should be understood that various modifications and adaptations thereof may be made within the spirit of the invention as set forth in the appended claims.

What is claimed is:

1. A telephone transmitter comprising a housing of insulating material, a resistance unit centrally disposed therein, comprising a metal bellows serving as an enclosure for said unit and electrically in contact therewith, a metallic diaphragm supported by said housing and arranged to exert pressure against said unit, and means for insulating said diaphragm from said unit.
2. A telephone transmitter in accordance with claim 1 wherein the end of said resistance unit has a depression therein, a washer of insulating material is positioned in said depression and said diaphragm has a projection extending into said depression and engaging said washer.
3. A telephone transmitter comprising a housing of insulating material having fixed thereto a first contact member provided with an aperture,

a variable resistance element comprising a metal bellows electrically constituting one terminal for said element said metal bellows having an insulated terminal post centrally disposed at one end thereof and constituting the other terminal for said element, means for fixing said post in said aperture to support said metal bellows in predetermined position with said one end adjacent said housing, means for applying a variable pressure to the other end of said bellows to vary the resistance of said element, and a second contact member fixed to said housing of insulated material and disposed to make contact with said metal bellows when the latter is supported in said predetermined position.

4. A telephone transmitter according to claim 3 wherein said post is screw-threaded in said aperture.

5. A variable resistance element comprising a metal bellows, an electrode within said bellows and electrically insulated therefrom, carbon granules within said bellows, means for insulating the inner side walls of said bellows from said carbon and an expansion chamber connected to said bellows.

6. A telephone transmitter comprising a metal bellows containing an electrode and granular carbon, an air-tight moisture proof seal for said bellows and an expansion chamber connected to said bellows.

7. A telephone transmitter comprising a first metal bellows containing granular carbon and having an electrode at each end thereof, one of said electrodes being insulated from said bellows and fixed thereto by means of an air-tight moisture proof seal, and the other of said electrodes being perforated and a second metal bellows fixed to said first metal bellows at the end adjacent said other electrode, said second bellows being weaker than said first bellows and serving as an expansion chamber.

8. A telephone transmitter comprising a chamber having a bellows-like portion of thin elastic metal and having an aperture in one end, granular carbon inside of said chamber, an electrode within said chamber, a molded insulating member having a metallic insert imbedded therein and extending therethrough, means forming an air-tight, moisture-proof seal between said member and said chamber for sealing said chamber from the atmosphere, and means connecting said insert to said electrode to provide electrical access to said electrode.

9. A telephone transmitter comprising a chamber having a bellows-like portion of thin elastic metal and having an aperture in one end, granular carbon inside of said chamber, an electrode having an enlarged head within said chamber and a shank extending through said aperture, insulating washers on said shank inside and outside said chamber, a nut on said shank for tightly clamping said washers against said chamber and said electrode to rigidly fix said electrode to said chamber and form an insulating granule-tight seal between said chamber and said electrode, a molded insulating member having a metallic insert imbedded therein and extending therethrough, means including said member for forming an air-tight additional insulating seal between said chamber and said electrode, and means connecting said insert to said shank to provide electrical access to said electrode.

ERNEST S. McLARN.
